UNITED STATES PATENT OFFICE.

HENRY DE BUS, OF CINCINNATI, OHIO.

MANUFACTURE OF BARRELS FOR WHITE ALCOHOLIC LIQUORS.

SPECIFICATION forming part of Letters Patent No. 226,044, dated March 30, 1880.

Application filed October 7, 1878.

To all whom it may concern:

Be it known that I, HENRY DE BUS, of Cincinnati, in the county of Hamilton and State of Ohio, have invented a certain new and useful

5 Improvement in the Art of Manufacturing Cooperage or Barrels for White Alcoholic Liquors, of which the following is a full, clear, and exact description.

New barrels or casks as heretofore manufactured could not be used with safety for white liquors, such as gin, white whisky, or spirits, because such liquors were liable to be discolored by such new casks, and to suffer in value in consequence. The discoloration was 10 caused either by the natural coloring-matter in the wood of the cask, or by the charred portions of the staves of a cask subjected to the ordinary firing process in its manufacture. Unsuccessful attempts have been made to remove 15 these coloring-matters from fired barrels by steaming them and subsequently subjecting them to an alum-wash. Such steaming and washing does not produce the desired effect on fired barrels not charred, for it appears 20 that the firing, while it has a tendency to draw the coloring-matters in the wood to the surface, in a manner crystallizes such coloring-matters, so that such steaming and washing can effect no removal thereof. In consequence 25 of these objections to the use of new casks, it has been customary to use stone jars, glass packages, and the like for the storage and transportation of these white liquors, and sometimes old barrels are used which had previously 30 contained an inferior liquor.

The object of my invention is to produce casks fit (when new) for the reception of white liquors; and to this end my invention consists

In carrying out my invention the staves should be set up at one end in truss-hoops, and while thus assembled they should be subjected to the action of steam in a steaming-box 50 to render them pliable. The steaming also has the effect of removing some of the coloring-matter from the wood, and of drawing, practically, all of it to the surface, where some of it remains. The steaming finished, the staves 55 are drawn into cask form, duly trussed, hooped, and headed, to make a finished cask. These various operations may be performed in the usual manner and by the aid of any suitable machinery. After the cask has been mechanically finished its interior is treated with an alum-wash, preferably hot.

The alum-wash may be made by dissolving alum in hot water, making a comparatively weak solution. The alum-wash will dissolve 65 and remove the remaining coloring-matters from the interior of the cask. The cask may finally be rinsed with clear water, either hot or cold.

I am aware that in the coopers' art steaming preparatory to or in the act of trussing has been practiced, and hence do not claim that; but

What I do claim, and desire to secure by Letters Patent, is—

The mode, substantially as before set forth, of removing coloring-matters from the staves of wooden casks in the course of manufacturing such casks, which mode consists of the following two essential steps, viz: steaming 80 the staves preparatory to trussing, (thereby avoiding firing of the same,) and treating the interior of the completed cask with an alum-
